UNITED STATES PATENT OFFICE.

JOHN WILLIAM NASMITH, OF MANCHESTER, ENGLAND, ASSIGNOR TO NASMITH'S PATENTS LIMITED, OF MANCHESTER, ENGLAND.

AUTOMATIC FEED DEVICE.

Application filed October 10, 1924, Serial No. 742,852, and in Great Britain October 27, 1923.

This invention relates to feeding mechanism for rotary scoring and cutting machines for the preparation of carton blanks—although as will be understood it can be 5 equally well applied to feeding mechanism for other machines into which it is required to feed single sheets from a pile of such sheets placed before it—and has for its object not only the feeding of such sheets but 10 also the automatic maintenance of the top of such a sheet pile at a proper level to enable the feeding devices to feed the top sheet to the usual gripper rollers, the sheet pile rising when the said pile has diminished. A further object is to so arrange 15 the mechanism for raising the sheet pile at the table on which it is borne so that it may be mounted in a truck which is movable to and from the feeding apparatus, without 20 detriment to the efficiency of the latter.

In carrying the invention into effect I provide a feeding device having gripper rollers as usual into the nip of which a sheet may be fed, and I also provide a vertically 25 movable table on which the pile of sheets rests. Mechanism is provided for raising the table. Feeding devices are provided to feed the top sheet of the pile to the gripper rollers, and these feeding devices operate a 30 clutch to put into motion or cause the cessation of rotation of a shaft which raises the table through transmission gearing. The feeding devices are normally in contact with the top sheet of the pile at each stroke, and 35 as they will fall as the pile diminishes and take a higher plane with the pile as the table rises, their reciprocatory motion effects the clutching or declutching of the mechanism according to their position. Diminution 40 of the pile is therefore automatically followed by raising the table, and when the said pile has been raised to the desired height again the raising mechanism is put out of gear until a further diminution takes place.

Although as will be obvious any known 45 methods of raising the table which bears the pile of sheets may be employed, such as for instance a screw jack or hydraulic jack or analogous means, a simple and efficient table raising means is specifically described hereinafter, which means will not be liable to be 50 knocked out of order.

Convenient means for carrying the invention into effect will now be described with 55 reference to the accompanying drawings,

which shows a side elevation, wherein Figure 1 is a side elevation; Figure 2 a plan; and Figure 3 an end elevation looking from the left of Figure 1; Figures 4 and 5 are respectively elevation and section of the 60 clutch mechanism shown in the preceding figures; and Figures 6, 7 and 8 are details to an enlarged scale of accessories through which the feeding devices operate the clutching and declutching of the table raising 65 mechanism.

Referring to the drawings F is a frame constructed to carry certain operative parts and is fixed in front of the machine to which the sheets of material have to be fed. In the 70 case of new machines this frame may be incorporated in the framework of the machine proper. In bearings in the lower part of the frame F, a shaft S is slowly and intermittently revolved by means that will be 75 described later.

A truck K is constructed with uprights U mounted at the four corners and suitably stayed, two of them being shown in the drawing, see Figure 1, and mounted on 80 wheels W. Fitted into the four uprights and at liberty to rise and fall vertically is a table T. It may be here observed that when desirable the said table may be incorporated in the machine itself, instead of forming 85 part of a truck. A pair of rollers R, R, are mounted on the framework to receive the sheets as fed and pass them on to the machine which is to operate on them.

Cast or fixed on each side of the truck 90 K are snugs 1, 2, 3, and fixed therein at each side are parallel shafts 4 on which blocks 5 are at liberty to slide. Similarly fixed or attached to the underside of the table T are snugs 6, 7, and 8, and a pair of parallel 95 shafts 9 on which slide blocks 10. Diagonal rods 11 and 12 (two at each side) are connected by a spring 12° and pivoted to the snugs 1 and 6 respectively and their opposite ends are pivoted on the blocks 10 and 5 100 respectively. A pin 13 connects the members of each pair of diagonals. Pivoted on pins in the blocks 5 are rods 14 (one on each side) whose outer ends are formed as racks to gear with pinions 15 keyed on the shaft S. The racks are kept in gear with the pinions 15 by cams 16 keyed on the shafts 17 carried in bearings formed in prolongations of the frame of the truck K. Levers 18 are also keyed on the shafts 17 110

and have connected to them drawbars 19 with a notch to engage with the pin 20. By releasing these the racks are dropped out of gear so that the truck K can be removed.

It is obvious that when the pinion 15 is revolved in the direction of the arrow the blocks 5 and 10 will be drawn forward on their rods 4 and 9 and the table T raised, whilst at the same time the truck K is drawn firmly against the frame F.

The shaft S receives its motion from an intermittently driven shaft 21 on which is mounted a worm 22 gearing with a worm wheel 23 keyed on the shaft 24 whereon is also keyed a worm 25 gearing with a worm wheel keyed on the shaft S. The manner in which the motion of this shaft is controlled by the height of the top sheet will be presently described.

When the machine is running the shaft 27 is continuously revolving, and keyed thereon (one at each end) are cams 28. These act on bowls 29 pivoted on pins in the end of levers 30 which are free to oscillate on studs 31 secured on the framing. Attached to the levers 30 at 32 are rods 33 free to slide vertically in grooves formed in the framing. Their upper ends are screwed to permit regulation of the gripping rail 34 which is mounted thereon. As the cam 28 revolves the rail falls at the appropriate moment into the top sheet of the pile and holds it.

The clutch employed, is of any convenient type. For instance the disc 35, notched internally as shown in dotted lines, revolves continuously and freely on the shaft 21. Keyed thereon is the usual block in which the pawl 36 is hinged. It is kept out of gear by the pin 37. As soon as this is withdrawn the pawl under the influence of the spring 37^a (shown dotted) engages with one of the notches in 35 and motion is communicated to the shaft 21 and the lever shaft S. The mechanism to put the pin 37 alternately in and out of action according to the height of the top sheet of the pile by means of the feeding devices is as follows. At each end of the shaft 27 is keyed a disc in which is fixed a crank pin 38 linked as shown to the lower end of lever 39, pivoted (one at each side) on the framing at 40. Hinged to the upper end of each of the levers 39 are rods 41 and as the crank revolves a to and fro motion is imparted to the rods 41 which are approximately horizontal. Transverse to the machine and mounted in bearings formed at the right hand end of the rods 41 is a shaft 41^a, upon which is mounted any suitable feeding device of known kind. For instance the usual rubber covered discs may be used, adjustable longitudinally along the shaft 41^a. As the rods 41 move from, left to right the shaft 41^a is allowed to revolve but is prevented

from doing so by the usual ratchet when the rods 41 are moving in the opposite direction so that the rubber covered discs grip the top sheet and feed one end forward, the sheet assuming a looped or curved form 70 as the gripping rail 34 is down on the other or forward end of the sheet. But as soon as the rail 34 is raised the sheet by its own resiliency straightens and shooting forward is seized by the gripper rolls R, and carried 75 forward thereby.

Sliding on a pawl 58 in a bearing 42 formed on the framing F is a rod 43 one end of which is hinged to a bell-crank lever 44 pivoted at 45. The other arm of the bell-crank 44 is provided with a slot 46 to receive the pin 47 which is secured to the clutch pin 37. Fixed on the rod 43 are collars 48 and 49 and a block 50 free to slide slightly thereon. A link 51 connects the block 50 to the lower end of lever 52 pivoted on the framing at 53. On the lever 52 are also hinged two adjustable catches 54 and 55 between which passes the rod 41 on which is secured an adjustable block 56. These members 54 and 55 are so hinged that they will not give way before the block 56 as the latter moves to the left of the figure, but will move freely on their hinges or pivots in the other direction, and they may be made adjustable upon the lever 52 by any known means.

As shaft 41^a descends as the paper pile diminishes, the reciprocatory movement of the arms 41 causes the block 56 borne by one of them to come into contact during the backward movement with catch 55 on arm 52, thus, through 51 and 43 and the bell crank lever bearing the pin 37, withdrawing the latter and putting in the clutch. Through the connected mechanism shafts 21 are thus rotated, worm wheels 26 and pinions 15 rotating in the direction of the arrow Figure 1 and drawing the racks 14 to the left of Figure 1, the table T thus being raised. The rod 43 thus again rising with the pile, its next backward reciprocation brings collar 56 into contact with catch 54, thus restoring the arm 52 to its former position and through the connecting members withdrawing the pin 37 of the clutch, rotation of shaft 21 being thus stopped automatically.

Removal of the truck when empty, and reengagement thereof with the pinions 15 through racks 14 are effected by means of the drawbars 19 as previously explained.

The truck when it bears the table T and the raising mechanism becomes a part of the feeding mechanism, but it will be understood that should circumstances make it desirable in any case the members U may be a fixture and act as the frame for the table, the pile of sheets being placed on the said table, and replenished as required. The em- 130

ployment of the truck is however a conspicuous advantage, as it saves transference of the pile of sheets from a conveyance on to the table.

5 I claim:—

1. An automatic feed device for feeding sheets singly from a sheet pile, comprising gripper rollers, a vertically movable table on which the sheet pile rests, feeding devices

10 to feed the top sheet of the pile to the gripper rollers, a truck on which the table is borne, means carried by the truck for raising the table bearing the sheet pile, a shaft put in rotation or stopped by clutch means 15 operated by the movement of the feeding devices, and transmission gearing between said shaft and the table raising mechanism, part of such gearing being borne by the truck and separable from the other and stationary transmission elements.

20 2. In apparatus as claimed in claim 1, feeding devices for the top sheet of a sheet pile, comprising hinged longitudinally movable feed rods engaging such sheet and reciprocated from a driving shaft their free ends normally resting upon the sheet pile, a vertically movable gripper rail to come down upon the forward end of the sheet pile, and a cam to raise the said gripper rail and allow it to drop upon the sheet pile by gravity, its length of downward traverse increasing as the sheet pile diminishes, and a clutch put into operation at a predetermined point in such downward traverse 30 and out of operation by the rising feed rods, for the purpose hereinbefore set forth.

35 3. In apparatus as claimed in claim 1, a shaft actuating the transmission gearing to raise the table and for declutching same, and means for clutching and declutching the said shaft by the movement of the feeding devices such means comprising a longitudinally movable rod one end of which actuates the clutch, the other end having pivoted thereto the end of a short oscillatory lever arm pivoted to the apparatus fram-

ing and bearing catches which come into the reciprocatory path of the feeding devices as the latter rise and fall with the sheet pile, substantially as hereinbefore set forth. 50

4. In apparatus as claimed in claim 1, means for raising the table bearing the sheet pile, such means comprising in duplicate a diagonal rod the upper end of which slides on a bearing on the table, the lower end being pivoted to the framing, a further diagonal rod pivoted centrally to the first rod, the upper end of such further rod being pivoted to the table and its lower end being 55 slidable, a rack connected to such slidable lower end, and transmission gearing between the clutch operable shaft and the rack to move the latter to vary the angles made with each other by the diagonal rods to raise the table borne thereby. 60

5. In apparatus having a movable table borne upon a truck as claimed in claim 1, racks directly connected to and operating the table raising means carried by the truck, such racks meshing with the transmission 70 gearing from the clutchable shaft, a transverse shaft having cam surfaces thereon to make contact with the lower faces of the racks to keep them in mesh with the said transmission gearing, and an adjustable 75 lever to give angular motion to such shaft.

6. In apparatus as claimed in claim 1, transmission gearing between the rotatable shaft and the table raising means proper, such transmission gearing consisting of a 80 worm on the said rotatable shaft meshing with a worm wheel on a second motion shaft, a further worm drum on such second motion shaft meshing with a worm wheel on a further shaft, and a toothed wheel compounded with the latter worm wheel such toothed wheel meshing with a toothed member of the table raising mechanism to operate the same. 85

In testimony whereof I have hereunto set 90 my hand.

JOHN WILLIAM NASMITH.
